UNITED STATES PATENT OFFICE

ERICH H. LICHTENBERG, OF MILWAUKEE, WISCONSIN, ASSIGNOR TO KOEHRING COMPANY, OF MILWAUKEE, WISCONSIN, A CORPORATION

BATCHMETER PRELIMINARY ALARM

Application filed July 19, 1929. Serial No. 379,471.

This invention has to do with devices for regulating the mixing period of a batch of concrete in a concrete mixing machine. Devices for accomplishing this result are known 5 as batchmeters. In the ordinary type of batchmeter, such as is described in Patent No. 1,451,483, to O. H. Winkler, the operator is given a signal to notify him that the mixing period is terminated, so that he can then 10 raise the loading skip for supplying the mixing drum with another batch of concrete.

The construction of the above noted Patent No. 1,451,483 presents certain objectionable features. First, in the case of use of 15 said batchmeter with a mixing machine wherein the skip is raised manually, inasmuch as the operator ordinarily does not have his hand on the skip hoist lever during the latter part of the mixing period, there will 20 be some loss of time between the batchmeter signal and the engagement of the skip hoist clutch. While this time loss may amount to only a few seconds on each batch, it may total considerable time during a working day. 25 Secondly, in the case of a mixing machine wherein the raising of the skip is automatic, the signal indicating the termination of the mixing period is simultaneous with the engagement of the skip hoist clutch for raising 30 the skip. This raising of the skip without warning may be dangerous if there are men working around the skip. And if there is a truck standing on the skip when the skip hoist clutch is engaged, serious damage is 35 more than likely.

The present invention is designed to eliminate the above noted undesirable features. To these and other ends I provide a preliminary or warning signal and means for 40 operating the same at a time prior to the final batchmeter signal, with mechanism for varying the time interval to meet the various exigencies incident to operation of the mixing machine. Thus, in the case of a mixing machine in which the skip is raised manually, 45 my novel preliminary signal warns the operator that the mixing period is about to end so that he is in position to operate the skip hoist when the period is ended. Moreover, in 50 a mixing machine wherein the engagement of

the skip hoist clutch is automatic, the function of the preliminary signal is even more important. With machines of the automatic type it is possible for the operator to disconnect certain parts from automatic operation. For example, the skip hoist clutch may be disconnected from the batchmeter. With my invention, the operator receives warning that the mixing period is almost over and the skip hoist about to start. If men 55 are working at or near the skip or a truck is on the skip, or if there is any other reason why the skip should not be raised at the end of the mixing period, the operator can disconnect the skip hoist from automatic operation before the mixing period ends.

In carrying out my invention, which may be applied to any type of batchmeter, I provide special mechanism connected with the operating means of a batchmeter and operable thereby to provide a warning signal prior to the completion of the mixing period of a mixing machine. This mechanism, in contemplation of my invention, is made adjustable to 70 vary the time interval between the warning signal and the termination of the mixing period. It is to be understood, however, that instrumentalities entirely separate from the batchmeter operating means may be availed 75 of for operating the warning signal.

More particularly, I provide a signalling means comprising a bell and hammer therefor, although gongs of different pitch, lights and the like may be used for the same purpose, the hammer being in the form of a plunger which is constantly urged toward the bell by gravity, a device normally holding the plunger out of contact with the bell, timing mechanism for controlling the time of operation of the bell, and means controlled by the timing mechanism which, at a predetermined instant, releases the plunger, which thereupon falls and strikes the bell.

With these and other objects and advantages in view, my invention comprises certain other novel combinations, constructions, and arrangements of parts as will hereinafter become apparent.

For a full and more complete understanding of the invention, reference may be had 100

to the following description and accompanying drawings, in which—

Figure 1 is an elevational view, partly in section, of my improvement applied to a batchmeter disclosed in Patent No. 1,451,483 of H. O. Winkler.

Figure 2 is a view similar to Figure 1, but on a somewhat smaller scale, showing my invention in detail and diagrammatically certain of the related parts of the batchmeter to which my invention is applied.

Figure 3 is an end view of a part of the signal operating mechanism forming a part of my invention, illustrating the way in which the time of operation may be varied.

For the purpose of illustration, my preliminary signalling device is shown by the drawings as applied to a batchmeter such as is disclosed in the Winkler Patent No. 1,451,483, although it is to be understood that it can be utilized in connection with any type of batchmeter wherein such a device is found desirable. In the drawings, reference numeral 1 indicates a batchmeter casing in which a main shaft 5 is housed. Rigidly secured to shaft 5 is a resetting arm 8, and loosely mounted on shaft 5 is an escapement operating lever 10. The outer end of lever 10 has a weight 12. The escapement mechanism is of any suitable type and is housed in a box 17. A skip (not shown) is operatively connected with shaft 5 so that raising of the skip causes shaft 5, and thereby arm 8, to turn counter-clockwise. Pivoted to the lever 10 is a dog 34, having a projection 33 which normally overlies the nose 9 of arm 8. The lever 10 is thus swung upwardly with the resetting arm 8 until the dog 34 is disengaged from the resetting arm 8.

In this connection it will be noted that the dog is formed with a lateral wing 35 which is adapted to engage an adjustable abutment such as the stem of a clamping screw 36 which is utilized to secure a block 37 in an adjusted position upon a quadrant 38. As soon as the wing 35 engages the abutment thus provided, the dog 34 is swung outwardly and disengaged from the nose of the resetting arm 8, thereby enabling the latter to continue in its upward movement independently of the escapement operating lever which has thus been released and now starts upon its return movement. The quadrant 38 may be suitably marked, as shown at 39 to indicate the proper positions for the block 37 to obtain the desired mixing period. By moving the block up or down upon the quadrant 38 the mixing period can be increased or decreased, as desired, and the device can be set within proper limits for any desired mixing time, as may be dictated by the character of materials being mixed, the kind of work being done, or the type of mixing machine in connection with which the batchmeter is used.

As soon as the escapement operating lever

10 is disengaged from the resetting arm 8 it starts upon its downward movement which is governed by the escapement mechanism, and when the loading skip C is lowered the resetting arm 8 is immediately returned to its original position by the action of the spring 32. At the lower limit of its movement the escapement operating lever 10 engages an abutment 40 projecting from the back of the casing. The resetting arm 8 is limited in its movements by a pair of abutments (not shown).

Depending from the resetting arm 8 is a hook member 43 which is formed with a cam tail piece 44. The hook member may be pivotally connected to the resetting arm in any suitable manner. In the present instance, it is rigid with a shaft 45 which extends through the resetting arm.

The control lever 49 is mounted upon a shaft 50 which extends rearwardly through the casing 1, and is urged upwardly by the spring 54. A pawl 55 hangs from the end of the control lever 49 which is remote from the stud 48, said control lever being pivotally mounted between its ends, and retained in position upon the shaft 50 by means of a collar 56 which is rigidly secured to the shaft in any suitable manner. A spring 57 engages the pawl 55 and normally tends to hold the same in a yielding engagement with a fixed pin 58 which projects from the back of the casing. At the lower end of the pawl 55 is a hooked nose which is arranged for engagement with one end of a tappet operating lever 59, said lever being pivotally mounted between its ends at 60 and the other end thereof of engaging a tappet rod 61 which extends slidably through the bottom of the casing 1 and is operatively associated with the mechanism of a conventional bell member 62, so that a signal is given by sounding the bell when the tappet rod is forced downwardly by the lever and released. This ringing of the bell constitutes a signal means for indicating to the attendant that the mixing period has ended and the discharge lock been released, so that he can cause the batch to be discharged from the mixer. The swinging movement of the tappet operating lever 59 is limited by an abutment 63 which projects from the bottom of the casing.

When the resetting arm 8 is at the lower limit of its movement the hook member 43 is in engagement with the stud 48 of the control lever 49. When the loading skip is swung upwardly to charge the mixing drum the resetting arm is swung upwardly. The control lever 49 is then swung upon its bearing and moved against the action of the spring 54. This results in lowering the pawl 55 and bringing the hooked nose thereof into an operative engagement with the end of the tappet operating lever 59. At the same time, the extremity of the control lever which is

provided with the stud 48 is brought into engagement with a locking detent 64, whereby the control lever is prevented from being returned to its original position by the action of the spring 54 until after the locking detent 64 has been released. As soon as the control lever has thus been swung into operative position and engaged by the locking detent 64, the cam tail piece 44 of the hook member 43 engages a fixed stud 65 projecting from the back of the casing and is thereby swung laterally out of engagement with the stud 48 of the control lever. This enables the resetting arm to continue in its upward movement independently of the control lever. Upon the return or downward movement of the resetting arm 8, the hook member 43 slips over the stud 48 of the control lever and resumes its original position.

The locking detent 64 is pivoted upon a pin 66 projecting from the back of the casing 1, and a spring 67 normally tends to urge the same into operative position. A rearward extension 64^a of the locking detent projects into the path of an adjustable abutment 68 on the escapement operating lever 10. The member 68 is in the form of a pin which has a threaded engagement with the lever 10 so that it can be adjusted in and out, and a locking nut 69 is provided for holding the pin in an adjusted position. The adjustment is such that when the escapement operating lever 10 reaches the lower limit of its movement, the pin or abutment 68 engages the rearward extension 64^a of the locking detent 64 and swings the said detent against the action of the spring 67 to disengage the nose thereof from the control lever 49. Upon being thus released the control lever is swung back to its original position by the action of the spring 54. The pawl 55 is thereby moved upwardly and the tappet operating lever 59 operated to ring the bell. The pawl 55 is formed with a cam 70 which cooperates with a fixed stud 58 projecting from the back of the casing to swing the pawl laterally against the action of the spring 57 and disengage the hooked nose thereof from the tappet operating lever 59 after the latter has been moved a sufficient amount. Upon being thus released, the tappet operating lever 59 returns to its original position in engagement with the abutment 63, its end nearest the pawl 55 being heavier than its opposite end, and when the control lever 49 is again swung into operative position by the upward movement of the resetting arm 8, the pawl 55 is guided into operative engagement with the end of the tappet operating lever 59 and the parts thereby set in proper position for another operation.

In the operation of the device, the block 37 is moved to an adjusted position upon the quadrant 38, depending upon the length of time it is desired to subject each batch of

materials to the action of the mixer. The mixing period is lengthened by moving the block upwardly upon the quadrant, and shortened by moving the block downwardly upon the quadrant. The scale 39 upon the quadrant enables the block to be accurately set according to the mixing time which has been determined upon.

After the block 37 has been properly adjusted upon the quadrant 38, the mixer is charged in the usual manner by means of the loading skip. The loading skip acts to move the resetting arm 8 upwardly, and this in turn acts to swing the escapement operating lever 10 upwardly into operative position, and also to move the control lever 49 into operative position. When the escapement operating lever 10 reaches the lower limit of its movement at the termination of the mixing period, the locking detent 64 is moved to release the control lever 49 which is then swung by the action of the spring 54 to actuate the signal, and release the discharge chute locking means.

Thus far I have described the mechanism of the batchmeter of the patent above noted. I shall now proceed with a description of the preliminary signalling device which I have designed to act in conjunction with said mechanism.

I accordingly provide a bracket 71 which is secured to the casing in any suitable manner, said bracket having an upstanding non-circular guide portion 72. A plunger or hammer 73 of corresponding non-circular shape rides in said guide portion and said plunger is constantly urged downwardly by gravity in the direction of the bell 62 by a heavy head 74 thereon. The head 74 has a guide 75 through which the link 76 slides, said link having heads 77, 78 to prevent said link passing through said guide. The head 78 is loosely secured to lug 79 on the arm 8. Thus when the skip is raised, the arm 8 is raised, carrying along with it link 76. When the head 77 reaches the guide 75, further upward movement of the link causes upward movement of the plunger 73 until the arm 8 has reached its uppermost position. The plunger 73 is provided with a notch 80 and the bracket 71 is provided with an opening 81. Pivottally secured to the bracket 71 at 82 is an arm 83 provided with a lug 84 which fits into opening 81 and is constantly urged into said opening and into contact with the plunger 73 by a spring 85 which is secured to both the bracket 71 and the arm 83. The notch 80 and the nose of the lug 84 are similarly shaped and when the lug fits into said notch the plunger is prevented from downward movement but not from upward movement with respect to said lug. Between the nut 69 and the lever 10 and surrounding the abutment 68 is a dog 86 which may be adjustably secured circumferentially of the

abutment 68. One end of a member 87 is rigidly secured to the arm 83 and said member is curved upwardly and to the right. The upper portion of the member 87 is in the path of downward movement of the dog 86 and when the dog 86 strikes the member 87, the latter together with the arm 83 and lug 84 will be cammed to the right. When the dog 86 moves upward, the spring 85 brings the dog 84 back to the opening and in contact with the plunger 73. Disposed between the upper end of the guide portion 72 and the head 74 is a spring 88 which functions to remove the plunger 73 from contact with the bell after the bell has been struck thereby to thereby avoid damping of the sound. This spring 88 is sufficiently weak so that it will not interfere with the downward movement of plunger 73 as it is about to strike.

10 The operation of the preliminary alarm device is as follows:—When the skip is raised the resetting arm 8 is raised and consequently through the medium of the link 76 engaging the guide 75 the plunger 73 is raised. After 15 the skip has been raised the arm 8 returns to its original position and while returning, the plunger 73 is permitted to slide downwardly until the wall of the notch 80 is engaged by the nose of the lug 84. Further downward 20 movement of arm 8 has no effect on the plunger 73. The lever 10 descends slowly and is governed by the escapement mechanism in the casing 17 as above noted. When 25 the dog 86 engages the member 87, which 30 engagement occurs a few seconds before the rearward extension 64^a is tripped by the abutment 68, the lug 84 is withdrawn from the notch 80 and the plunger 73 at this point falls and strikes the bell 62. This, as above 35 explained, warns the operator that the mixing period is about to terminate so that by the time it does terminate, he is in a position to immediately operate the skip hoist clutch, in the case of a manual skip hoisting device, 40 or to prevent motion of the skip in the case of an automatic hoisting device, to avoid any danger that might be imminent. When the escapement operating lever 10 is almost at the end of its downward travel, it operates 45 the regular batchmeter signal, indicating the end of the mixing period. It may be desirable to have the length of time between the preliminary alarm and the final signal adjustable so as to obtain a longer or shorter 50 warning as may prove desirable under the particular operating conditions. This is provided for in the possibility of adjustment of the dog 86 as hereinabove described. It is clear from the illustrations, particularly 55 Figure 3, that with the dog adjusted to the position shown in dotted lines, the dog will engage the member 87 and consequently withdraw lug 84 from notch 80 sooner than when 60 the dog is in the position shown in full lines.

65 Having thus described my invention, what

I claim as new and desire to secure by Letters Patent of the United States, is—

1. In a batchmeter, mechanism for timing the mixing period of a mixing machine, a signal adapted to operate prior to the termination of said period, a signal adapted to be operated at the termination of said period, and means for operating both of said signals. 70

2. In a batchmeter, mechanism for timing the mixing period of a mixing machine, a signal adapted to operate prior to the termination of said period, a second signal adapted to operate at the termination of said period, operating means associated with said mechanism for operating said signals, and means for varying the time interval between said signals. 75

3. In a batchmeter, mechanism for timing the mixing period of a mixing machine, a signal adapted to operate prior to the termination of said period, a signal adapted to be operated at the termination of said period, means for operating both of said signals, and timing instrumentalities for controlling the time at which the preliminary signal is operated. 80

4. In a batchmeter, mechanism for timing the mixing period of a mixing machine, a signal adapted to operate prior to the termination of said period, a signal adapted to be operated at the termination of said period, means for operating both of said signals, and timing instrumentalities for controlling the time of operation of the last mentioned signal. 85

5. In a batchmeter, mechanism for timing the mixing period of a mixing machine, a signal adapted to operate prior to the termination of said period, a signal adapted to be operated at the termination of said period, means for operating both of said signals, and timing instrumentalities for controlling the time of operation of said signals. 90

6. In a batchmeter, mechanism for timing the mixing period of a mixing machine, a signal adapted to operate prior to the termination of said period, a signal adapted to be operated at the termination of said period, means for operating both of said signals, timing instrumentalities for controlling the time at which the preliminary signal is operated, and means for varying the time interval between said signals. 110

7. In a batchmeter, mechanism for timing the mixing period of a mixing machine, a signal adapted to operate prior to the termination of said period, a signal adapted to be operated at the termination of said period, means for operating both of said signals, timing instrumentalities for controlling the time of operation of the last mentioned signal, and means for varying the time interval between said signals. 120

8. In a batchmeter, mechanism for timing the mixing period of a mixing machine, a signal adapted to operate prior to the termi- 125

nation of said period, a signal adapted to be operated at the termination of said period, means for operating both of said signals, timing instrumentalities for controlling the time of operation of said signals, and means for varying the time interval between said signals.

9. In a batchmeter, mechanism for timing the mixing period of a mixing machine, a preliminary signal adapted to operate prior to the termination of said period, a final signal adapted to operate at the termination of said period, means for operating said preliminary signal, instrumentalities for operating said final signal, and a timing device for controlling the time of operation of said preliminary signal.

10. In a batchmeter, mechanism for timing the mixing period of a mixing machine, a preliminary signal adapted to operate prior to the termination of said period, a final signal adapted to operate at the termination of said period, means for operating said preliminary signal, instrumentalities for operating said final signal, and a timing device for controlling the operation of said final signal.

11. In a batchmeter, mechanism for timing the mixing period of a mixing machine, a preliminary signal adapted to operate prior to the termination of said period, a final signal adapted to operate at the termination of said period, means for operating said preliminary signal, instrumentalities for operating said final signal, and a timing device for controlling the time of operation of said signals.

12. In a batchmeter, mechanism for timing the mixing period of a mixing machine, a preliminary signal adapted to operate prior to the termination of said period, a final signal adapted to operate at the termination of said period, means for operating said preliminary signal, instrumentalities for operating said final signal, and means for varying the time interval between the operation of the preliminary and the final signals.

13. In a batchmeter, mechanism for timing the mixing period of a mixing machine, a preliminary signal adapted to operate prior to the termination of said period, a final signal adapted to operate at the termination of said period, means for operating said preliminary signal, instrumentalities for operating said final signal, a timing device for controlling the time of operation of said preliminary signal, and means for varying the time interval between the operation of the preliminary and the final signals.

14. In a batchmeter, mechanism for timing the mixing period of a mixing machine, a preliminary signal adapted to operate prior to the termination of said period, a final signal adapted to operate at the termination of said period, means for operating said preliminary signal, instrumentalities for operating said final signal, a timing device for

controlling the operation of said final signal, and means for varying the time interval between the operation of the preliminary and the final signals.

15. In a batchmeter, mechanism for timing the mixing period of a mixing machine, a preliminary signal adapted to operate prior to the termination of said period, a final signal adapted to operate at the termination of said period, means for operating said preliminary signal, instrumentalities for operating said final signal, a timing device for controlling the time of operation of said signals, and means for varying the time interval between the operation of the preliminary and the final signals.

16. In a batchmeter, a signal, a tappet for operating said signal, mechanism for timing the mixing period of a mixing machine, means urging said tappet toward said signal, means normally holding said tappet out of engagement with said signal, and instrumentalities associated with said mechanism for rendering said holding means inoperative prior to the termination of the mixing period.

17. In a batchmeter, a signal, a tappet for operating said signal, mechanism for timing the mixing period of a mixing machine, means urging said tappet toward said signal, means normally holding said tappet out of engagement with said signal, instrumentalities associated with said mechanism for rendering said holding means inoperative prior to the termination of the mixing period, and means for drawing said tappet out of contact with said signal after the operation of said signal.

18. In a batchmeter, a signal, a tappet for operating said signal, mechanism for timing the mixing period of a mixing machine, means urging said tappet toward said signal, means normally holding said tappet out of engagement with said signal, and instrumentalities associated with said mechanism for rendering said holding means inoperative prior to the termination of the mixing period, and means for varying the time interval between the end of the mixing period and the operation of the signal.

19. In a batchmeter, a signal, a tappet for operating said signal, mechanism for timing the mixing period of a mixing machine, means urging said tappet toward said signal, means normally holding said tappet out of engagement with said signal, instrumentalities associated with said mechanism for rendering said holding means inoperative prior to the termination of the mixing period, means for drawing said tappet out of contact with said signal after the operation of said signal, and means for varying the time interval between the end of the mixing period, and the operation of said signal.

20. In a batchmeter, mechanism for timing the mixing period of a mixing machine,

an escapement device associated with said mechanism, a signal member, a plunger disposed vertically and adapted to strike said member under the influence of gravity, means normally holding said plunger out of contact with said member, and a dog secured to said mechanism for rendering said holding means inoperative at a predetermined instant prior to the termination of the mixing period, whereby said plunger may fall and strike the signal member.

In testimony whereof I affix my signature.
